INCANDESCENT ELECTRIC LAMP

Filed Dec. 20, 1928

UNITED STATES PATENT OFFICE

WILLIAM L. CUMMINGS, OF BERWYN, ILLINOIS, ASSIGNOR TO THE ELECTRON RELAY CORPORATION, OF CHICAGO, ILLINOIS, A CORPORATION OF ILLINOIS

INCANDESCENT ELECTRIC LAMP

Application filed December 20, 1928. Serial No. 327,325.

This invention relates to incandescent electric lamps and relates particularly to a type of such lamps known as "white lights" designed and adapted for use in television, photography and related fields.

Objects of the invention are to provide a lamp of the type specified which will develop or produce an intense or brilliant light, which has capacity for rapid changes in light 10 intensities and will retain its characteristic light qualities through a wide range of intensity variations, and which is rich in actinic rays.

To effect the objects of the invention, a 15 lamp embodying my invention and improvements comprises the various features, combinations of features and details of construction hereinafter described and claimed.

In the accompanying drawings, in which 20 my invention is fully illustrated—

Figures 1 and 2 are, respectively, central sectional views of what I now consider to be a preferred form of lamp embodying my 25 invention and improvements, taken at angles of 90 degrees to each other, Fig. 2 being on the line 2—2 of Fig. 1;

Figure 3 is a fragmentary sectional view, substantially on the line 3—3 of Fig. 1;

Figure 4 is a detached detail view; and

Figure 5 is a side view, partly in section, 30 of a lamp embodying my invention in modified form, certain features thereof being indicated diagrammatically.

Describing the invention with particular 35 reference to the drawings and referring, in the first instance, to Figs. 1 to 4, in which I have shown what I now consider to be the preferable form of lamp embodying my invention, my improved lamp, designated as 40 a whole A, is a form of incandescent lamp, comprising a hollow glass bulb a, which, as shown is substantially spherical and comprises a neck portion a', providing means for securing a base of usual form, not shown, 45 thereto, for supporting said bulb and for making electrical connections thereto. As regards its usual features and except as hereinafter may be particularly described and pointed out, the bulb a—including said base— 50 may be of any usual or approved construc-

tion and can readily be understood and supplied by artisans skilled in the art, from an examination of the drawings, without a description thereof in detail.

The lighting element of the lamp comprises 55 a filament or filaments 1 and an equal number of field coils 2 electrically connected in series and mounted in such relative positions that a filament and a field coil will always extend substantially parallel with each other, 60 with the filament in the magnetic field which surrounds the field coil directly associated therewith. In practice, I prefer to use a plurality of filaments and field coils, and the lamp shown in Figs. 1 to 4 is of this character.

The filaments 1 will preferably be made of tungsten or platinum wire or other suitable metal or substance, which will be coated with an oxide of cerium or neodymium or 70 other suitable rare earth having the quality of producing "white light" when heated to incandescence.

The field coils 2 are made of wire—preferably silver or copper wire—which has low 75 resistance to the passage of electric currents.

Within the scope and contemplation of my invention, the filaments 1 and field coils 2 are connected to one another to form an alternate series, in any usual or desired manner, preferably by spot-welding.

As shown, there are four filaments 1 and four fields coils 2, but my invention contemplates varying the number of filaments and field coils to meet any desired requirements.

As shown, the filaments 1 and field coils 2, connected in the manner described, are supported in operative relation by means as follows: Embedded in a solid enlargement 80 3, formed at the inner end of a tubular inward extension 4 of the neck portion a' of the bulb a, is a short wire 5 which is a good conductor of electricity—preferably silver or copper wire—the embedded portion of said 95 conductor being looped, as shown at 6, thus insuring a very strong anchorage. The ends of said conductor diverge upwards and project outside of the enlargement 3, as shown at 7. Also embedded in said enlargement 3 100

are conductor wires 8 and 9, the ends of which project into the hollow interior of the bulb α . As shown, a field coil 2 is connected to the projecting inner end of the conductor 8 and the filament 1 associated therewith, to the proximate end 7 of the conductor 5, a filament 1 and associated field coil 2 being connected, respectively, to the other end 7 of the conductor 5 and to the projecting inner end of the conductor 9.

As indicated diagrammatically in the drawings, the conductors 8 and 9 are adapted to be connected electrically with an outside source of electrical energy, as the power tube 15 of the amplifier of a radio receiving set, by outside conductor wires 8' and 9'. In practice, such electrical connections may conveniently be made by means of a usual base, not shown, forming part of the lamp A, in a 20 usual manner.

As shown, also, the ends of the filaments 1 and field coils 2 other than those connected to the looped conductor 5 and the conductors 8 and 9, are connected by short conductors 10 and 11, which pass around lugs 12 and 13 formed on separate wire arms 14 and 15 embedded in a head 16 formed on the upper end of a post or standard 17 on the enlargement 3, the relation being such that said filaments 30 1 and field coils 2 will form a plurality of substantially symmetrical parts or sections—as shown two—each consisting of what may be designated two strands, the strands of each part or section extending substantially parallel with each other and each comprising the same number of filaments and field coils, the filaments of each strand being positioned in the magnetic field surrounding a field coil in the other strand of said part or section.

40 I prefer, in accordance with common practice, that the bulb α will be exhausted to a high vacuum.

In accordance with known practice and methods, the metallic parts enclosed in the bulb α will be degassed to prevent the generation of gases in said bulb under heat or electrolytic action, which might impair or adversely affect or modify the designed operation of the lamp.

50 As a modification of my improved lamp, I contemplate the use of additional field coils, preferably mounted exteriorly to the container for the filament or filaments and the field coil or coils directly associated therewith, 55 said additional field coils being connected in electrical series with said filament or filaments and directly associated field coil or coils, and coupled to produce desired inductive effects between said filament or filaments 60 and directly associated coil or coils and said additional coils, whereby, upon the passage of electric current through said field coils, stresses will be imposed upon the filament or filaments and directly associated coil or coils, 65 which will produce variations in amplitudes

or wave forms, thus causing variations in light intensity proportional or relative to changes or variations in input signals or impulses.

This modification is shown in Fig. 5 of the drawing, in which A' designates the lamp as a whole, α^2 the glass container—shown as forming a tube of substantially uniform diameter, α^3 the neck of the container providing means for securing thereto a base, not shown, 1' and 2' the filaments and field coils, respectively, which form the lighting element, and which are electrically connected in series and are mounted within the container α^2 in substantially parallel relation and substantially co-extensive with each other.

70 Except as regards structural details, the foregoing and other features of the lamp A' corresponding to features of the lamp A, shown in Figs. 1 to 4 and heretofore described, will be readily understood by persons skilled in the art from an examination of said Fig. 5 without a further description thereof in detail.

75 As heretofore generally described, also, the lamp A' comprises additional field coils indicated diagrammatically at 18 and 19, which are connected in series with each other and also with the filament 1' and field coils 2' directly associated therewith, by the conductor wires 8², 9², and which are mounted outside thereof and preferably outside of the container α^2 , and are coupled to produce desired inductive effects between the same in the manner and for the purpose specified.

80 I claim:

1. An incandescent electric lamp for the purpose specified, comprising a lighting element consisting of a filament and a field coil electrically connected in series, means for mounting said filament and field coil in substantially parallel relation with the filament in the magnetic field surrounding said field coil, said filament and field coil having high and low resistances to electric currents, respectively, and a coating applied to said filament having the property that it will emit white light of high actinic value when heated to incandescence.

85 105 110 115 120 125 130

2. An incandescent electric lamp as specified in claim 1, in which the filament and field coil are of substantially equal length and co-extensive.

3. An incandescent electric lamp as specified in claim 1, which comprises a plurality of filaments and field coils connected electrically in alternate series.

4. An incandescent electric lamp as specified in claim 1, in which the filament is coated with an oxide of a rare earth having the quality of producing white light of high actinic value, when heated to incandescence.

5. An incandescent electric lamp for the purpose specified, comprising a lighting element consisting of a filament and a field coil

electrically connected in series, means for mounting said filament and field coil in substantially parallel relation with the filament in the magnetic field surrounding said field coil, said filament and field coil having high and low resistances to electric currents, respectively, a coating applied to said filament having the property that it will emit white light when heated to incandescence, and additional field coils which surround the filament and field coil directly associated therewith and connected in electrical series therewith and also with each other, and are coupled to produce inductive effects between the same upon the passage of electric currents.

6. An incandescent electric lamp as specified in claim 5, in which the additional field coils are mounted exteriorly to the container for the filament and directly associated field coils.

In witness that I claim the foregoing as my invention, I affix my signature this 17th day of December, 1928.

WILLIAM L. CUMMINGS.
